C. C. Stirling Inventor
By his Attorney
Frost Luton

UNITED STATES PATENT OFFICE.

CLARENCE C. STIRLING, OF HARTFORD, CONNECTICUT.

ELECTRIC SWITCH.

Application filed January 5, 1921. Serial No. 435,061.

To all whom it may concern:

Be it known that CLARENCE C. STIRLING, a citizen of the United States, residing at Hartford, in the county of Hartford and 5 State of Connecticut, has invented certain new and useful Improvements in Electric Switches, of which the following is a specification.

This invention relates to electric switches 10 and more especially to a handle or knob therefor. While it is conceivable that the improvements are capable of general use in the art set forth, they are of particular utility when employed in connection with 15 rotary snap-switches. A rotary snap-switch comprises a spindle which is mounted for turning movement and which is equipped with a handle or knob. These handles or knobs generally have a threaded 20 connection with their spindles. As a consequence of this manner of assemblage, it becomes an easy matter to remove a handle by simply unscrewing it. The fundamental 25 object of the invention is to provide a handle or knob for a switch of the kind set forth and which when it is in assembled relation and when turned in the proper manner will effect the action of the spindle and through the latter the switch mecha- 30 nism but which has means of an effective and positive nature for positively locking it against surreptitious removal but which when occasion requires, can be readily taken off.

35 In the drawings accompanying and forming part of the present specification, I have shown in detail one of the several forms of embodiment of the invention which to enable those skilled in the art to practice the 40 invention will be set forth fully in the following description. I am not restricted to this particular disclosure. I may depart therefrom in several respects within the scope of the invention defined by the claim 45 following said description.

Referring to said drawings:

Figure 1 is a side elevation of a rotary snap-switch equipped with a handle involving the invention.

50 Fig. 2 is a top plan view of the same.

Fig. 3 is a transverse section on the line 3—3 of Fig. 2.

Fig. 4 is a bottom plan view of the handle or knob.

Like characters refer to like parts 55 throughout the several views.

A rotary snap-switch generally comprises a base as 2 usually of some insulating material. Rising from the base is a spindle 3 with which is customarily associated snap-switch mechanism such as that denoted in a general way by 4, the switch mechanism being co-operative with contacts as 5 fixed on the base 2. The switch mechanism is housed in a metallic casing as 6 which has 60 a slot 7 in its top by which the index member 8 fastened to the spindle 3 for rotation therewith, can be read. The index member has on its surface the words "On" and "Off" so that by glancing through the slot 7 the 65 condition of the switch can be at once determined. The rotation of the spindle 3 brings about the desired action of the switch mechanism.

Associated with the spindle 3 or its 75 equivalent is a handle or knob such as that denoted by 9 which is usually made of some insulating material such as vulcanized rubber. The upper end of the spindle 3 is externally threaded as is usual for the detachable connection therewith of a sleeve or tube 10 which is situated in a chamber or socket 11 in the handle or knob 9, the sleeve or tube extending as shown a short distance below the body of the handle or knob 9. 80 The sleeve or tube 10 as represented has at its upper end an annular flange 12 which bears as shown against the top of the chamber or socket 11. The internal diameter of the cylindrical chamber or socket 11 is 85 somewhat greater than the external diameter of the sleeve or tube 10 so as thus to provide a space or interval for the reception of a coiled spring constituting a 90 convenient means for a purpose as I will herein-after explain. The sleeve or tube 10 which of course is externally plain, slidably receives around it the washer or disk 13 against which the forward end of the coiled spring 14 bears the rear end of the spring 100 having a bearing against the annular flange 12 and the spring acting constantly to advance the disk or washer 13 against the diametrically-opposite stops or shoulders 15 in the chamber or socket 11. Turning movement of the washer or disk 13 is positively prevented, for instance by the diametrically- 105 opposite keys 16 embedded in the stock of

- the handle or knob 9 and extending almost entirely throughout the depth of the chamber or socket 11, the keys fitting diametrically-opposite keyways or notches in the 5 peripheral portion of the washer or disk 18. The handle or knob 9 as shown has extending depthwise thereof the pin 17, this pin as will hereinafter appear being capable of clutch connection with the spindle 3.
- 10 The pin 17 is held in place for instance by a transverse key 18 and it extends depthwise of the handle or knob 9. Its lower end portion is situated within the socket or chamber 11 and also within the upper end 15 portion of the sleeve or tube 10. As illustrated the pin 17 has at its lower end a fin or key 19 co-operative with a transverse groove or slot 20 in the upper end of the spindle 3.
- 20 The manner of mounting the handle or knob 9 is as follows. The upper end of the spindle 3 will be engaged with the internal threads of the sleeve or tube 10 at which time the handle or knob 9 will be turned to 25 the right until the handle or knob 9 abuts against the casing 6. Just about this time the clutch portion or fin 19 will strike the slotted end of the spindle. The threaded surface of the spindle and sleeve or tube 10 30 are of such pitch that after a number of turns have been made, the fin 19 will bottom in the slot or groove 20 so that the walls of the slot or groove effectually prevent backward movement of the button in 35 a direction to permit wrongful removal of the same unless the button or knob be retracted and turned backward several times, the number of backward turns depending on the pitch of the thread of the spindle 3.
- 40 I have found by making this thread of a certain pitch, four backward movements of the button and the simultaneous backward

rotation thereof during each backward movement will be requisite to effect the removal of the button.

It will be clear from the foregoing description taken in connection with the annexed drawings that I provide a button or handle for the spindle of an electric switch that cannot be turned backward or taken from the spindle without retracting the button and turning it backward while it is in the retracted relation. In the construction shown it is necessary to retract the button or handle and turn it backward 50 several times before it can be separated from the spindle. The clutch button therefore is capable when properly assembled with the spindle of rotating it in one direction but is rigid with the spindle and therefore incapable of disengagement by merely backward rotation because to separate it it must be drawn back and at the same time reversely turned, several of these actions 55 as I have noted being necessary to effect its separation from the spindle.

What I claim is:

A button for the spindle of an electric switch, provided with a clutch portion in the form of a fin to engage the slot on the switch 70 spindle, and a coiled spring around the spindle acting to yieldingly lock the fin into the slot to prevent backward motion of the button when it is operatively connected with the spindle, said spring acting to permit the button to be freed from the spindle by the retraction and the backward motion of the button.

In testimony whereof I affix my signature.

CLARENCE C. STIRLING.
